PRELIMINARY TRACK FORMING SANDER
FOR BOWLING ALLEYS

Giovanni Parovel, Sacramento, Calif.

Application March 19, 1951, Serial No. 216,391

9 Claims. (Cl. 51—176)

1

This invention relates generally to sanding machines for bowling alleys; it being requisite that the floor of bowling alleys be recurrently sanded to maintain them perfectly smooth and level.

The finish sanding operation involves the use of a full width sanding machine such as shown in my copending application, Serial No. 216,390, filed March 19, 1951, the machine traveling lengthwise of the alley on transversely spaced wheels which ride paths or track along opposite side edges of the bowling alley floor.

In order to avoid the necessity of repeatedly leveling the finish sanding machine, it is a major object of this invention to provide a preliminary sander, of novel construction and function, operative to sand said paths or tracks—along opposite side edges of the bowling alley floor—whereby to level the same lengthwise for subsequent tracking thereon of the wheels of said finish sanding machine. The latter, traveling on the preleveled tracks, thus does not require repeated longitudinal leveling adjustment.

Another important object of the invention is to provide a preliminary sander, as above, which embodies the novel combination of an initially separate elongated, portable base track, and a sanding carriage slidably but removably supported thereon; the base track and carriage, being separable, facilitating station to station manipulation of said base track as required in use of the machine.

A further object of this invention is to provide a sanding machine constructed to permit of ready and convenient replacement of the expendable sanding paper with which the sander drum is faced.

An additional object of the invention is to provide a sanding machine which is compact and sufficiently light in weight that it may be readily moved along the alley as the preliminary sanding operations progress.

Still another object of the invention is to provide a sanding machine which is designed for ease and economy of manufacture.

It is also an object of the invention to provide a practical and reliable sanding machine, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the sanding ma-

chine, with the hood shown in section to more clearly reveal the general construction.

Fig. 2 is a cross sectional elevation taken at the center of the sanding drum looking toward the adjustment means for the drum.

Fig. 3 is a perspective view of the detached track.

Fig. 4 is an end view of the track detached, with a portion broken away to reveal the adjustment screw means.

Fig. 5 is a fragmentary section of one hold-down lip on the movable carriage.

Referring now more particularly to the characters of reference on the drawings, the track forming sander for bowling alleys consists of two initially separate units, one being an elongated portable base track, indicated generally at 1, of rigid construction, and the other being a sanding carriage, indicated generally at 2.

20 The elongated base track 1 consists of side rails 3, with laterally inwardly projecting top flanges 4, and the side rails 3 are connected, at the ends, by cross ties 5. The top surfaces 6 of the flanges 4 have a straight, accurately machined finish, 25 and thereby provide a way upon which the bottom surface 7 of the relatively short sanding carriages 2 may slide with level or straight line travel; said carriage riding on the base track 1 when the machine is in use.

30 The sanding carriage 2 consists of a cast, longitudinal frame 8 which includes side webs 9 and opposite end cross members 10 and 11, front and rear, respectively, which connect between said webs.

35 An electric motor 12 is mounted on the frame 8 of the sanding carriage 2 adjacent the rear end of the latter, and such motor drives a reduction gear box 13 whose output shaft is fitted with a pulley 14; there being an endless belt 15 trained 40 at one end about the pulley 14 and at the other end driving a sanding drum 16 by means of an end pulley 17.

The sanding drum 16, which is relatively narrow, carries on its periphery a removable sanding belt 18; such drum being mounted on a cross shaft 19, and on which shaft the pulley 17 is fixed.

45 The shaft 19 rides, immediately beyond opposite ends of the sanding drum 16, in bearing blocks 20 slidable in vertical slots 21 formed in the sides or webs 9 of the frame 8.

The bearing blocks 20 are engaged in yielding relation from below by compression springs 22; such springs being capable of supporting the weight of the sanding drum 16, bearing blocks 20, 50 and the associated parts.

55

Exact vertical positioning or adjustment of the bearing blocks 20, and consequently the sanding drum 16, is maintained by plungers 23 holding down against the tops of said bearing blocks 20; such plungers depending in pivotal relation from corresponding arms 24 which radiate from a cross shaft 24a. The arms 24 are adjusted vertically by an adjustment screw 25 which bears against a dog 26 which upstands from the cross shaft 24a; the screw being threaded through the end cross member 10. Thus, by the simple adjustment of the single screw 25 the working position of the sanding drum 16 is accurately and effectively set.

The bearing blocks 20 have inner flanges 27 which bear against the center hub 28 of the sanding drum 16, thereby serving to maintain said drum in centered alignment in the frame 8, i. e. centrally between the webs 9; the drum being of a diameter such that it projects some distance below the bottom of the frame 8.

A hood H, which may be swung clear, normally covers the sanding drum 16 and adjacent parts; said drum, when swung clear, exposing the sanding drum for easy change of the sanding paper or sleeve on said drum.

When the machine is in use, the elongated, portable base track 1 is located lengthwise on the floor of the bowling alley immediately adjacent one gutter 29 thereof; such locating being facilitated by sets of spring-advanced plungers 30 mounted in the track 1 along the sides thereof, one set depending into the gutter and bearing against the side edge of the bowling alley floor; the latter being indicated at 31. As the plungers 30 are spring-advanced, the set which rests on the bowling alley floor 31, as set at 32, automatically retracts and does not interfere with the aforesaid positioning of the base track 1.

The base track 1 is leveled by vertical adjusting screws 33 which extend through the cross ties 5; there being a spirit level 34 set lengthwise in the base track 1 intermediate its ends whereby to indicate when said base track is level.

Thus, during operation of the machine, the sanding carriage 2 slides on the top surface 6 of flanges 4 in a perfectly level path, and so that the sanding drum 16 which extends to the bowling alley floor 31 will sand a smooth pathway along the latter for the length of travel of said sanding carriage 2 along the base track 1. Such pathway or track will be perfectly level due to the hereinbefore described leveling of the base track 1, and the level sliding of the sanding carriage 2 thereon.

When the sanding operation is completed in a first position, the machine is moved to a second position along the length of the bowling alley, with the base track 1 partially overlapping its previous position; the base track 1 then again being adjusted level, and a continuing pathway or track is sanded on the same level as before. This operation is repeated until the length of the bowling alley has been traversed and a continuous pathway or track sanded level near the edge of the bowling alley floor 31. The base track 1 is then shifted to the other side of the alley and the operations are repeated.

After continuous level pathways or tracks have been sanded by the machine along opposite sides of the bowling alley floor 31 immediately adjacent the gutters 29, the alley floor is sanded by the full width finish sanding machine as shown in the aforesaid copending application. By reason of the fact that the finish sanding machine

has wheels which run on the pre-leveled continuous pathways or tracks, it is unnecessary that repeated longitudinal leveling adjustment of such machine be made.

The sanding carriage 2 is maintained in guided relation on the base track 1 by means of depending flanges 35 on the frame 8 riding against the inner edges of the flanges 4. Additionally, hold-down lips 36 are provided at the leading end of the sanding carriage 2 at the sides thereof and in position to under-lie the flanges 4, whereby to prevent the carriage from tending to rise from the base track 1 for any reason. These lips may be turned, to clear flanges 4 when it is desired to lift the carriage from the base track, by a combination turning and locking unit 37 connected to each lip.

The sanding carriage 2 is moved along the base track 1 by means of a conventional form of handle 38 which projects upwardly from the rear end of said flange.

This invention provides a very practical, reliable, and useful machine for the preliminary sanding of level, straight-line pathways or tracks along opposite sides of a bowling alley floor preparatory to a finish sanding machine working along the alley with wheels which travel said tracks.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A sanding machine, operative to level a trackway along an outer edge portion of a bowling alley floor, comprising a single rigid elongated base track adapted to rest lengthwise on said outer edge portion of the bowling alley floor, said base track being longitudinally straight on top, means on the base track to level the same, a carriage supported on and movable along the base track on top thereof, a sanding drum journaled on the carriage in position depending for sanding engagement with said floor only adjacent the track and said outer edge portion of the floor, and power means on the carriage driving the sanding drum.

2. A sanding machine, operative to level a trackway along an outer edge portion of a bowling alley floor, comprising a single rigid elongated base track unit adapted to rest lengthwise on said outer edge portion of the bowling alley floor, said base track unit having transversely spaced longitudinal ways thereon and being open top to bottom between said ways for a major portion of its length, means on the base track unit to level the same, a carriage supported on and movable along said ways, a sanding drum journaled on the carriage in position depending between said ways for sanding engagement with said floor, and power means on the carriage driving the sanding drum.

3. A sanding machine, as in claim 2, in which the sanding drum is relatively narrow.

4. A sanding machine, operative to level a trackway along an outer edge portion of a bowling alley floor, comprising an elongated base

track adapted to rest lengthwise on said outer edge portion of the bowling alley floor, said base track being initially separate, portable, and having relatively close transversely spaced longitudinal ways thereon, the base track being open top to bottom between said ways for a major portion of its length, a vertically separate carriage removably supported on and movable along said ways, a sanding drum journaled on the carriage in position depending between said ways for sanding engagement with said floor, and power means on the carriage driving the sanding drum.

5. A sanding machine, operative to level a trackway along an outer edge portion of a bowling alley floor, comprising an elongated base track adapted to rest lengthwise on said outer edge portion of the bowling alley floor, said base track being initially separate, portable, and having transversely spaced longitudinal ways thereon, the base track being open top to bottom between said ways for a major portion of its length, a vertically separate carriage removably supported on and movable along said ways, a sanding drum journaled on the carriage in position depending between said ways for sanding engagement with said floor, and power means on the carriage driving the sanding drum; the carriage including spaced sides having transversely aligned vertical slots therein, bearing blocks slidable vertically in the slots, the sanding drum having a center shaft journaled in said bearing blocks, and means to vertically adjust the bearing blocks in unison.

6. A sanding machine, as in claim 5, in which said last named means comprises compression springs engaging the bearing blocks from below, plungers engaging the bearing blocks from above, a cross shaft on the carriage, radial arms on the cross shaft pivoted to the plungers, a dog projecting from the cross shaft, and an adjustment screw threaded in connection with the carriage and abutting said dog.

7. A sanding machine, operative to level a

trackway along an outer edge portion of a bowling alley floor, comprising an elongated base track adapted to rest lengthwise on said outer edge portion of the bowling alley floor, said base track being initially separate, portable, and having transversely spaced longitudinal ways thereon, the base track being open top to bottom between said ways for a major portion of its length, a carriage supported on and movable along said ways, a sanding drum on the carriage depending between the ways for floor engagement therebetween, and locating elements depending from the base track adjacent one edge adapted to project into the gutter of the bowling alley in side engagement with the floor.

10 8. A sanding machine, as in claim 7, in which said locating elements are spring pressed plungers; there being a longitudinal set of such elements along the other edge of the base track.

15 9. A sanding machine to level a trackway on a bowling alley floor immediately adjacent and lengthwise of a gutter of the alley, said machine comprising a rigid elongated track unit adapted to rest on the alley floor, means to locate the unit immediately adjacent and lengthwise of the gutter, said unit including a pair of transversely separated rigid ways and means connecting said ways at their ends only, a carriage supported on and movable along the ways, and a sanding drum mounted on the carriage and depending between the ways for floor engagement.
